UNITED STATES PATENT OFFICE.

HARRY HOLLINGS, OF OTLEY, ENGLAND.

AUTOMATIC SHEET-FEEDER FOR PRINTING AND FOLDING MACHINES AND THE LIKE.

942,036.

Specification of Letters Patent. Patented Nov. 30, 1909.

Application filed June 26, 1909. Serial No. 504,632.

To all whom it may concern:

Be it known that I, HARRY HOLLINGS, a subject of the King of the United Kingdom of Great Britain and Ireland, and resident 5 of Mount Pisgah, Otley, Yorkshire, England, have invented new and useful Improvements in Automatic Sheet-Feeders for Printing and Folding Machines and the Like, of which the following is a specification.

This invention relates to an improved construction of automatic sheet feeder for printing and folding machines and the like, and has for its object to insure the feeding from 15 a pile of sheets, of one sheet at a time. The feeding of one sheet at a time from a pile of sheets is effected by means of a segmental suction roller and a coöperating wiper roller or brush, said suction roller being rotated 20 and carrying the sheet of paper around with it until the roller has performed a half circle, when the suction is cut off from the roller and the sheet is carried forward to the table or the tapes of the printing machine.

25 In my improved construction of automatic sheet feeder, the paper is completely turned over.

Figure 1 shows a front elevation of the sheet feeding machine; Fig. 2 is a view at 30 right angles to Fig. 1, looking toward the right, and for the sake of clearness the standards of the machine are shown in dotted lines; Figs. 3, 4, 5 and 6 are end views of the suction roller or pickerup—in different 35 positions; Fig. 7 is a side elevation of the top portion of the frame showing the approximate position of the picking-up roller and the carrying forward device for the paper; Fig. 8 is a detailed plan view of the 40 carrying forward device; Fig. 9 shows the means for arresting the upward movement of the paper table while a sheet is being removed therefrom by the segmental vacuum roller; Fig. 10 shows means for oscillating 45 the side arms which carry the segmental vacuum roller; and Fig. 11 shows how the gate is set for keeping the rear edges of the paper in position.

Referring to Figs. 1 and 2, the numerals 50 1 and 2 designate the side standards of the machine, within which are journaled the operating shafts A, B, C and D. From the said shaft A, the rods a at each side of the standards 1 and 2 are operated, being given 55 a rocking motion so as to reciprocate the rollers a^1 (see Figs. 7 and 8) for transfer-

ring the sheet of paper to the printing machine table, or the tapes thereof, from the suction picking-up roller A¹.

At the top of the standards of the machine 60 and carried by the arms A² is the suction picking-up roller A¹. These arms are given a rocking motion similar to the rods a , from the shaft B, and the said arms A² of the vacuum picking-up roller A¹ are formed at 65 their free ends as a bracket head b^3 , to accommodate a train of three toothed wheels A⁴, a^1 , a^2 , and between the arms A² and also carried thereby are the wiper rollers B¹ which are for the purpose of removing from 70 the vacuum picking-up roller A¹ any surplus sheets, that is, to allow only one sheet at a time being carried forward by said roller. The sheets, in case more than one is picked up by the roller A¹, are wiped or 75 stroked off by the rollers B¹ and are at the same time placed back again in position on the pile of sheets so that they are in correct position for the next operation of the roller A¹. The toothed wheel A⁴ is carried on the 80 same axle as the vacuum roller A¹ but the small wheels a^1 , a^2 are to one side of the toothed wheel A⁴. The said wheel a^2 is keyed or otherwise secured to the end of the spindle of the rollers B¹ and through the 85 partial rotation of the wheel A⁴ and the intermediate toothed wheel a^1 , the toothed wheel a^2 is driven and imparts a counter-clockwise motion to the rollers B¹. Similarly the vacuum roller A¹ is partially ro- 90 tated.

Carried by the frame at one side and at the top thereof, I provide the toothed rack A⁵ and the arrangement of the vacuum roller and its gear wheels and wiper rollers 95 B¹ is such that the arms A² are caused to rock by reason of an extension A² carrying a roller x at its free end, engaging with a cam x^1 on the shaft C whereby the wheel A⁴ is rotated by the rack A⁵ and so turns over 100 the vacuum picker-up A¹ and imparts a motion of rotation to the rollers B¹.

In Fig. 3 of the drawings, I have shown the suction roller A¹ in a position for picking up a sheet of paper. In Fig. 4, is shown 105 the roller having picked up a single sheet and with the pressure of the paper underneath removed. In Fig. 5 is shown the suction roller partially rotated and with the rollers B¹ in action so as to remove any additional sheets of paper. In Fig. 6 is shown the roller A¹ having performed its motion 110

of rotation and with its sheet of paper in a position for being removed from the roller, the suction having been cut off from the said roller. In the last figure (Fig. 6), the roller has traversed as well as rotated, that is, the arms A^2 have transferred it to the position shown in Fig. 7.

The means for creating a vacuum in the roller A^1 consists of a pump C^1 having in communication therewith a pipe a^3 which leads to the hollow spindle of the suction roller A^1 ; the roller having a channel along its length with the outlets such as a^4 . The pump C^1 has its piston rod g connected to the rocking lever C^2 (Fig. 2) which is pivotally mounted on the shaft D . This rocking lever C^2 carries a roller c^1 , which rides upon the cam c^2 on the shaft C as said shaft C is rotated and thus the plunger of the cylinder C^1 is caused to set up a suction in the roller A^1 and when it has described its required rotation the rod d opens a valve in the pump cylinder and the vacuum therein, and consequently in the roller A^1 , is destroyed. To actuate the rod d , there is provided on the shaft A a two-armed member D^1 , one of which members is connected to the rod d and the other is adapted to be engaged by the cam D^2 of the shaft C (see Figs. 1 and 2). The timing of the vacuum in the roller A^1 is determined by the required traverse thereof.

Beneath the roller A^1 is provided a table or platform E carrying the pile of sheets of paper to be fed to the printing machine. This table is given a rising and stop or intermittent motion by providing the underside of the platform with the carrying or supporting bar e which is formed or provided with the rack portion e^1 , and the position of the table is determined by means of the quadrant toothed wheel J which is in gear with the rack portion e^1 of the bar e . Formed or provided on the side of the quadrant J is the toothed or ratchet wheel e^2 and intervening between the side of the bracket and the side of the said toothed wheel e^2 , is provided the coil or other spring F which is for the purpose of tensioning the quadrant J in a counter-clockwise direction. When the table E is in its lowermost position, the arrangement is such that the winding up of this spring puts the same in tension and causes the quadrant J to have a clockwise motion and by reason of being in gear with the toothed portion e^1 of the platform or table E , the table is given an upward motion carrying with it the sheets of paper.

When the paper is in contact with the underside of the roller A^1 , it is necessary to temporarily remove the pressure beneath the same. (See Fig. 9.) This is caused by preventing the quadrant from moving, and to effect which the shaft D is provided with a pawl g^1 which is operated by the cam f of the shaft C in such a manner that when the

pressure is to be removed from the table, the cam f forces up the pawl g^1 until the free end engages with the ratchet wheel e^2 whereby the upward motion of the table is arrested. As the cam f rotates, the pawl g^1 falls by gravitation clear of the ratchet wheel e^2 of the quadrant J .

On the front of the machine and abutting the edge of the table is arranged the gate H which is pivotally mounted at h on the brackets h^1 which are supported on the stretcher G between the standards. The portions h^2 forming the gate may be threaded on to a square shaft h^3 with rounded journaled ends h^4 , and intervening between the underside of the stretcher G and the square shaft h^3 there may be a couple of flat springs in contact with the top of the flat portion h^3 of the gate after the manner shown in Fig. 11, and the arrangement is such that when the gate is in its vertical position, the spring retains it.

The shaft C is the main driving shaft of the machine and it has keyed on it the pinion C^3 , outside the standard, and is in gear with a similar pinion C^4 and it derives its motion therefrom. The pinion C^4 is mounted on a stud shaft and has secured to its face a large pinion C^5 preferably with teeth of a coarser pitch which is in gear with the printing machine whereby the feeding device is driven.

The arms a which support the roller a^1 for carrying forward the paper from the feed roller A^1 , are given a rocking motion by means of the arrangement shown in Fig. 10, which is a view looking to the left of Fig. 1. Outside the standard is mounted on the shaft C the disk C^6 having pivoted to it and eccentric of its axis, the rod C^7 which is in turn connected to the arm C^8 of the side rod a and the arrangement is such that as the disk C^6 is rotated, the rod C^7 imparts a rocking motion to the arms a on the shaft A . With further reference to the function of the rollers a^1 (as shown more particularly in Figs. 7 and 8), for the purpose of feeding or transmitting a sheet of paper from the segmental shaped vacuum roller A^1 to the usual traversing tapes of a printing machine, I provide a small trolley frame such as shown in Fig. 8 carrying the wheels a^1 , the said frame being supported and actuated by the rod a^{1x} , which is in turn carried by the shaft a^{2x} journaled at each end in the arms a and being carried thereby and the arrangement is such that when the sheet of paper has assumed the position shown in Fig. 7 the vacuum is cut off from the roller A^1 and the rollers a^1 wipe the sheet off the roller by reason of the rear traversing movement thereof caused by the rotary movement of the arms a , that is to say, the roller a^1 strokes the sheet of paper off the roller A^1 on the platform A^{1x} and

thence from the end of the said platform to the traversing tapes of the machine, whereby it is conducted to the desired position.

5 The operation of the machine is as follows:—The sheets of paper to be fed to the usual running tapes (or table) of the printing machine, are placed on the table E (Fig. 1) and the segmental vacuum picking-up roller A¹ is caused to come into contact with the top sheet of paper. The vacuum roller A¹ picks up one sheet, and if it picks up more than one sheet, the friction rollers B¹ which rotate against the 15 vacuum roller A¹ will stroke off the additional sheet. When the vacuum picking-up roller has thus carried the sheet, the vacuum is cut off from the said roller and the rollers a¹ stroke the sheet off the vacuum picking-up roller and feed the sheet forward to the running tapes (or table) of the printing machine. This completes the operation of the vacuum picking-up roller and it returns to its normal position, viz., that as 25 shown in the full lines in Fig. 2.

What is claimed is:

1. In a sheet feeding machine, the combination with a suitable frame having a shaft journaled therein, of a pair of rocking arms 30 mounted on said shaft, a sheet delivering device carried by said arms, a second shaft journaled in the frame, a pair of rocking arms mounted on said second shaft, a suction device mounted on said second pair of arms 35 and adapted to coöperate with the delivering device and feed the sheets thereto, a table, for supporting the sheets to be fed, a rack bar on said table, a toothed quadrant

mounted on said first-named shaft and engaging with the rack, a spring on the first-named shaft adapted to normally tension 40 the quadrant and elevate the table to position the pile of sheets to be fed, means for stopping the upward pressing of the table, when the topmost sheet of the pile has been 45 engaged by said suction device, and gearing connections between the said shafts.

2. In a sheet feeding machine, the combination with a suitable frame having a shaft journaled therein, of a pair of rocking arms 50 mounted on said shaft, a sheet delivery device comprising a laterally disposed shaft having rollers carried by said rocking arms, a table on the frame on which said rollers are adapted to travel, a second shaft journaled in the frame, a pair of rocking arms mounted thereon, a suction device mounted on said second pair of arms and adapted to coöperate with the delivering device and feed the sheets thereto, a third shaft mounted in the frame, a pump actuated through the medium of the third shaft and adapted to effect suction in the suction device, means for breaking the suction therein, a table for supporting the sheets to be fed, resilient 55 means mounted on the first shaft and connected thereto and adapted to intermittently elevate said table by the rotation of said shaft and position the pile of sheets to be fed, means for limiting the upward 60 movement of said table, and gearing connections between the several shafts.

HARRY HOLLINGS.
